UNITED STATES PATENT OFFICE.

WILLIAM J. GUY, OF NEW YORK, N. Y.

DESIGN FOR A SHORTHAND NOTE-SHEET.

No. 39,492.

Specification for Design.

Patented Sept. 1, 1908.

Application filed May 14, 1908. Serial No. 432,948. Term of patent 14 years.

To all whom it may concern:

Be it known that I, WILLIAM J. GUY, a citizen of the United States, residing in the city of New York, borough of Manhattan, in the county and State of New York, have invented a new, original, and ornamental Design for Shorthand Note-Sheets, of which the following is a specification, reference being had to the accompanying drawing, forming a part thereof

The figure is a face view of a shorthand note sheet, illustrating my new design.

I claim:

The ornamental design for a shorthand note sheet, as shown.

WILLIAM J. GUY.
